(57) **CLAIM**

The ornamental design for a set of adhesive tapes, as shown and described.

DESCRIPTION

FIG. 1 is a bottom, rear, right perspective view of a first adhesive tape in a set of adhesive tapes, showing our new design;

FIG. 2 is a top, front, left perspective view thereof;
FIG. 3 is a bottom plan view thereof;
FIG. 4 is a top plan view thereof;
FIG. 5 is a rear elevation view thereof;
FIG. 6 is a front elevation view thereof;
FIG. 7 is a right side elevation view thereof;
FIG. 8 is a left side elevation view thereof;
FIG. 9 is a top, perspective view of the first adhesive tape in the set of adhesive tapes in an alternate configuration, in use as applied to a human hand;
FIG. 10 is a perspective of view thereof as applied to the underside of the human hand;
FIG. 11 is a bottom, rear, right perspective view of a second adhesive tape in the set of adhesive tapes, showing our new design;
FIG. 12 is a top, front, left perspective view thereof;
FIG. 13 is a bottom plan view thereof;
FIG. 14 is a top plan view thereof;
FIG. 15 is a rear elevation view thereof;
FIG. 16 is a front elevation view thereof;
FIG. 17 is a right side elevation view thereof;
FIG. 18 is a left side elevation view thereof;
FIG. 19 is a top, perspective view of the second adhesive tape in the set of adhesive tapes in an alternate configuration, in use as applied to a human hand;
FIG. 20 is a perspective of view thereof as applied to the underside of the human hand;
FIG. 21 is a top, perspective view of the first and the second adhesive tapes in the set of adhesive tapes in a second alternate configuration, in use as applied to a human hand, with the first adhesive tape shown underneath the second adhesive tape; and,
FIG. 22 is a perspective of view thereof as applied to the underside of the human hand.
The portions in broken lines of even length depict a reference human hand and a third adhesive tape and form no part of the claimed design. Contrast in materials is shown by line shading in some areas and stipple shading in other areas.
